ROLLER SKATE RESILIENT HANGER
STRUCTURE

Robert R. Ware, Jr., Chicago, Ill., assignor to Chicago Roller Skate Company, Chicago, Ill., a corporation of Arizona

Application January 5, 1945, Serial No. 571,391

5 Claims. (Cl. 280—11.19)

1

The present invention relates to a roller skate, and more particularly to a resilient hanger structure therefor.

The present invention is directed to a roller skate of the type provided with resiliently supported axle mounting arranged to permit the axles to yield with respect to the body portion of the skate and to swivel about predetermined axes for shifting the wheels with respect to the body of the skate to facilitate turning and control by the skater. To provide such control there is embodied in the construction in accordance with the present invention a yielding or cushioning connection in the form of a cushioning member or buffer between the body of the skate and the axle.

In constructions of this type it has been found desirable to provide a resilient cushioning member which has the characteristic of a firm resistance to compression when the axle is in normal relation relative to the body of the skate, and a predetermined degree of freedom of movement to other positions of the axle relative to the body of the skate, which degree of freedom becomes less as the angular displacement of the axle increases from its normal position. In order to assure normal stability of the axle, a certain resistance must be provided in the cushioning member. At the same time a predetermined bending or flexing of the cushioning member is desirable to provide the yielding movement of the axle to facilitate turning and control by the skater. It has been found that a buffer of the cylindrical type commonly used heretofore does not provide the proper relation between the desired movements of the skate axles relative to the body. In accordance with the present invention a more nearly perfect degree of movement is obtained by providing a generally cylindrical apertured cushioning member having the material thereof so distributed as to provide a substantial resistance to an axial compressive force relative to the member and yet permit the necessary bending or flexing of the member when the axle is turned or displaced. This is obtained by cutting away portions of a generally cylindrical member by bores, grooves, cavities or recesses.

It is therefore an object of the present invention to obviate the aforementioned difficulties and to provide an improved resilient hanger structure for roller skates.

Another object of the present invention is to provide an improved resilient hanger structure for roller skates having a resilient member constructed to provide a maximum resistance to an

2

axial compressive force and a predetermined resistance to bending or flexing.

Other and further objects of the present invention subsequently will become apparent by reference to the following description taken in connection with the accompanying drawing wherein

Figure 1 is a perspective view of a roller skate embodying the present invention;

Figure 2 shows a portion of the roller skate of Figure 1 partially in cross section along an axial longitudinal plane;

Figure 3 is a rear view of that portion of the roller skate shown in Figure 2;

Figure 4 shows in perspective the preferred embodiment of a resilient cushioning member constructed in accordance with the present invention;

Figure 5 shows another modification of the invention shown in Figure 4; and

Figure 6 shows a further modification of the invention shown in Figure 4.

Referring to Figures 1, 2, and 3 of the drawing it will be seen that there has been shown a roller skate having a body portion or plate 10 of the type commonly permanently secured to the sole and heel of a skate shoe. The plate 10 of course may be provided with suitable heel portions where the skate is to be of the temporary attachable type. Immediately beneath the plate 10 there is a reinforcement plate 12 to which is secured the structure supporting the forward wheel or roller assemblies 14 and 16. Since both the forward and rear wheel assemblies embody the same principles further description of the invention will be restricted to the embodiment shown in Figure 2.

The reinforcement plate 12 is positioned between the plate 10 and a bracket 18 and secured by suitable rivets 20. The bracket 18 adjacent its forward end is provided with a socket 21 for receiving the ball end of an arm 22 which supports the forward axle 24 of the roller skate wheel assembly 14. To the rear of the axle 24 the bracket 18 is provided with an embossment 26 having a threaded aperture for receiving the threaded end of a stud bolt 28. Immediately beneath the embossment 26 there is one end of a strap 30 which together with a strap 32 constitutes a truss construction interconnected with the bracket 18 by suitable rivets such as the rivet 20 and the rivet 34. The end of the strap 30 is provided with a suitable clamping surface against which there is positioned a jam nut 36. Immediately beneath the jam nut 36 there is pro-

vided a cup 38 which is adapted to receive the upper end of a buffer or cushioning member 40. The lower end of the cushioning member 40 rests in a flange 42 extending from the lower end of the arm 22 which supports the axle 24. The flange 42 is provided with a frusto-conical recess or aperture 44 so as to permit a certain degree of movement of the stud bolt 28 relative to the flange 42. Interposed between the stud bolt 28 and the flange 42 is a suitable washer 46. The bracket 22 is provided with laterally extending integral sleeves 48 which house the axle 24 which serves to properly space apart the wheels 50.

Figure 4 in perspective shows a buffer 40 which is provided with a central aperture 52 for receiving the bolt 28. The buffer 40 has a generally cylindrical shape which is provided with a plurality of longitudinally peripherally arranged recesses 54. The recesses 54 extend from the bottom to within a short distance of the top where a cap-like portion 55 is provided for engagement with the cup 38. The cap-like portion 55 may be slightly larger than the remainder of the cylindrical shape so as to frictionally engage the sides of the cup 38. By providing the grooves or recesses which extend longitudinally with respect to the axis of the member 40, sufficient material is so distributed as to provide the maximum resistance to an axial compressive force and yet to provide the desired flexibility with respect to a bending or flexing action which decreases as the angle of flexure increases. By virtue of the frusto-conical recess 44 in the flange 42, it will be appreciated that a turning motion by the skater produces a flexing action on the buffer 40 which on one side of the skate is translated into a compressive action in the proximity of the outer surface of the member 40 so that the compressive resistance of a member decreases the flexibility so as to limit in proper degree the angular displacement of the roller skate axle 24 relative to the body 10.

A still further embodiment of the present invention is provided in Figure 5 wherein a generally cylindrical cushioning member or buffer 56 is shown provided with an axial recess 58 to accommodate the bolt 28. Between the inner and outer peripheries of the member 56 a plurality of longitudinally extending bores or cavities 60 are provided. These cavities 60 are selected in number and are spaced about the central cavity 58 so as to provide an action similar to the action provided in the construction shown in Figure 4.

A still further modification is shown in Figure 6 which shows a buffer 62 provided with a central cavity 64 to accommodate the bolt 28. The outer surface of what would otherwise be a generally cylindrical member is recessed as at 66 by a curved recess or surface so that the diameter of the member 62 at its mid-portion is appreciably less than at either end. Thus again the member is formed so as to provide a maximum resistance to an axial compressive force and yet provide a predetermined lesser degree of resistance to bending or flexing to permit the axle 24 to be displaced from its normal position for the proper control by the skater. In each of the embodiments shown in Figures 4 to 6 the cushioning member or buffer provides normal vertical stability of the skate and yet permits or facilitates displacement of the skate axle for universal swiveling about a predetermined point adjacent the front or rear portion of the skate.

While certain preferred embodiments have

been shown in the drawing for the purpose of illustrating and describing the present invention, it is to be understood that changes may be made in the form and construction and arrangement of the several parts without departing from the spirit and scope of the invention as set forth in the following claims.

This invention is hereby claimed as follows:

1. A roller skate construction comprising a body provided adjacent the end thereof with a socket bracket, roller carrying means including an arm having a ball mounted in said socket bracket, and a second bracket carrying a cushioning member interconnecting said body and said roller carrying means, said cushioning member comprising a fluted generally cylindrical member of resilient rubber-like material arranged to provide firm resistance to axial compression and a predetermined degree of freedom to torsional and bending pressure to permit displacement of the roller carrying means from normal position.

2. A buffer member for interconnecting the body of a roller skate with roller carrying means comprising a generally cylindrical member of resilient rubber-like material having a central aperture for mounting said buffer on said skate, said buffer formed with external integral splines to provide a desired resistance to an axial compressive force while facilitating bending and twisting of the buffer.

3. In a roller skate, the combination comprising a body adapted to be secured to a shoe, roller carrying means each having an arm connected to said body to permit pivotal movement of said arm relative to said body, means interconnecting said roller carrying means and said body comprising a bracket carrying a cushion, and a cushioning member of resilient rubber-like material having a generally cylindrical shape with longitudinally extending portions thereof cut away intermediate the ends to facilitate bending and twisting to a desired degree while maintaining a desired vertical stability of the roller skate, said cushioning member having a cap-like top forming an annular end portion adjacent one end, said top having a cross sectional area greater than the cross sectional area of said member intermediate the ends adapted to frictionally engage the sides of a cup member.

4. A buffer for a roller skate construction comprising a generally cylindrical member having a central aperture for mounting said buffer, said buffer being formed of a resilient rubber-like material with longitudinal grooves or recesses to facilitate bending and twisting of said buffer while maintaining a desired resistance to an axial compressive force, said buffer adjacent one end having an annular end portion which is greater in cross sectional area than the cross sectional area of said member intermediate its ends adapted to frictionally engage a cup member in a roller skate construction.

5. A roller skate construction comprising a body provided adjacent the end thereof with a socket bracket, roller carrying means including an arm having a ball mounted in said socket bracket, and a second bracket carrying a cushioning member interconnecting said body and said roller carrying means, said cushioning member comprising a generally cylindrical member of resilient rubber-like material, said member having a plurality of channels extending longitudinally thereof and arranged to provide firm resistance to axial compression and a predetermined degree of freedom to torsional and bending pressure to permit dis-

5

placement of the roller carrying means from normal position.
